UNITED STATES PATENT OFFICE.

ANDERS L. MORDT, OF GUYMON, OKLAHOMA.

DESIGN FOR A NUTCRACKER.

42,144.

Specification for Design.

Patented Feb. 6, 1912.

Application filed September 11, 1911. Serial No. 648,776. Term of patent 14 years.

To all whom it may concern:

Be it known that I, ANDERS L. MORDT, a citizen of the United States, residing at Guymon, in the county of Texas and State of Oklahoma, have invented a new, original, and ornamental Design for Nutcrackers, of which the following is a specification, reference being had to the accompanying drawing, forming a part thereof.

In Figures 1, 2, and 3 of the drawing, a nut cracker is shown in front and side view in closed position, and in side view in open position respectively.

Copies of this patent may be obtained for five cents each, by addressing the "Commissioner of Patents, Washington, D. C."

The new design consists in conforming the cracking jaws to represent the head of an old man wearing a cap.

I claim:

The ornamental design for a nut cracker as shown.

ANDERS L. MORDT.
